UNITED STATES PATENT OFFICE.

THOMAS A. SULLIVAN, OF CLAREMONT, NEW HAMPSHIRE.

PERFORATING ATTACHMENT FOR JOB-PRESSES.

1,175,570.

Specification of Letters Patent. Patented Mar. 14, 1916.

Application filed June 21, 1915. Serial No. 35,324.

To all whom it may concern:

Be it known that I, THOMAS A. SULLIVAN, a citizen of the United States, residing at Claremont, in the county of Sullivan, in 5 the State of New Hampshire, have invented a certain new and useful Improvement in Perforating Attachments for Job - Presses; of which the following is a specification, reference being had to the accompanying 10 drawings.

The object of this invention is to provide a simple inexpensive, and readily attachable, device for use with ordinary job presses, of the swinging platen type, for 15 perforating papers during the operation of printing the same; my said device being of such a novel construction that it may be quickly attached to such presses without the aid of tools other than an ordinary screw 20 driver or wrench, and which may be adjusted to punch a plurality of holes at any desired distances apart within the range of the device.

The annexed drawings illustrate my said 25 invention clearly, Figure 1 being a perspective view of the ink-disk, platen, and bed of a job press having my present improvement attached to the said platen. Fig. 2 is 30 a perspective view of the punch arm and of the die plate. Fig. 3 is a perspective view of one of the die-blocks and Fig. 4 is a similar view of one of the punch blocks.

In these drawings the numeral 20 indicates the ink table of a job printing press, 35 21 the impression bed and 22 the platen which is hinged at 23; said platen having hinged thereto the customary binders 24 and 25 for clamping the paper blanket to the platen.

40 Briefly described my present improvement comprises a counter-weighted arm which is hinged to the rear edge portion of the platen, and has adjustably mounted thereon one or more blocks with punches 45 that are adapted to co-act with dies that are fixedly attached to the said platen, the arrangement of parts being such that the punches and dies are in engagement during the brief period of impression and, when 50 the platen drops, after said impression, the

counter-weight, which I have incidentally mentioned above, separates the punches and dies in order that the sheet last perforated and printed may be removed and a fresh sheet substituted therefor.

55

Referring again specifically to the drawings, the numeral 26 denotes the punch arm or bar, the same being pivotally secured to one end of bar 33, and formed with a weight 28 at its lower end portion. The block 27 60 is adapted to be slipped over the rear edge portion of the platen and then to be clamped in its operative position by the closing down of the binder 25 as will be understood by reference to Fig. 1 of the drawings. Slidably mounted upon the bar 26 are blocks 29 which may be secured to said bar by screws 30 and each of which blocks carries a punch 31.

65

Attached to the outer edge portion of the 70 platen 22 and held in place by the closing down of the blanket binder 24, is a plate 32 to which is secured a flat bar 33 which lies on the platen or blanket and has adjustably mounted thereon plates 34, each of said 75 plates being bored to provide a die opening which will receive one of the described punches 31.

Assuming that there is a press fitted 80 with my described perforating attachment and that the punches and dies have been properly adjusted so that each punch is in register with its particular die:—the sheet to be printed and perforated is laid on the platen and suitably located by means of the 85 customary guide-pins. When the platen swings forward for an impression, the dies receive the punches, and the sheet located therebetween is perforated at the instant that said sheet received the imprint from 90 the printing form. When the platen drops back to its open position, the weight 28 in seeking to maintain the punch bar 26 in a vertical position, separates the punches from the dies, thus leaving the perforated 95 sheet free to be removed from the press.

Having thus described my invention, I claim as new and wish to secure by Letters Patent:—

1. In combination with a swinging-platen 100

printing press, a perforating attachment comprising a counter-weighted bar secured to said platen, punches adjustably mounted on said bar, a die plate secured to said platen, and dies adjustably mounted on said plate and adapted to co-act with said punches.

2. In a swinging-platen printing press, in combination with a platen thereof, blanket binders as described, and perforating devices mounted on said platen and secured thereto by the said binders. 10

THOMAS A. SULLIVAN.
